(57) **CLAIM**

The ornamental design for an inclined pillow with a depression feature, as shown and described.

DESCRIPTION

FIG. 1 is an isometric view of an inclined pillow with a depression feature showing my new design;

FIG. 2 is a top plan view thereof;

FIG. 3 is a side elevational cross-section view along line 3-3 thereof;

FIG. 4 is a front elevational view thereof;

FIG. 5 is a rear elevational view thereof;

FIG. 6 is a bottom plan view thereof; and,

FIG. 7 is a side elevational cross-section view along line 3-3 showing the inclined pillow with a depression feature in use. The broken lines shown in the drawings are included for the purpose of illustrating environmental structure and form no part of the claimed design.

1 Claim, 3 Drawing Sheets
